UNITED STATES PATENT OFFICE.

BENJAMIN H. TOQUET, OF WESTPORT, CONNECTICUT.

PENCIL.

SPECIFICATION forming part of Letters Patent No. 605,657, dated June 14, 1898.

Application filed June 19, 1897. Serial No. 641,473. (No model.)

To all whom it may concern:

Be it known that I, BENJAMIN H. TOQUET, a citizen of the United States of America, and a resident of Westport, Fairfield county, in the State of Connecticut, have invented an Improved Pencil, of which the following is a specification.

The ordinary wood-covered pencil, with graphite or other marking-core, is the cheapest form of pencil; but it has its disadvantages due to the need of sharpening the point by cutting away the covering and core by a knife or other means, and also in the consequent shortening of the pencil down to a useless stump. Endeavors have been made to do away with some of these disadvantages by making the covering of the core of layers of paper or wood, which can be removed by the finger as the core wears down, but such constructions have not been satisfactory. The most advantageous forms of pencils are those in which the core is moved forward within the cover or holder, which remains of uniform length notwithstanding the wear of the core, and in which the core can be removed; but all such pencils have been heretofore more or less expensive.

By my present invention I am enabled to make a very simple construction of pencil with a movable core to be fed forward as the point wears and at scarcely any greater cost than the ordinary wooden-sheathed pencil, which has to be sharpened with a knife or other such instrument.

In the accompanying drawings, Figure 1 is a longitudinal section of a pencil constructed in accordance with my invention. Fig. 2 is a view of a suitable pusher to be used for pencils of the construction shown in Fig. 1. Fig. 3 illustrates different forms of pawls which may be employed in my pencils. Figs. 4 and 5 are sectional views illustrating modifications.

Referring to Fig. 1, A is the covering or sheath, which may be made of any suitable material, such as wood or papier-mâché, but I prefer to use wood, such as employed in the manufacture of the ordinary "lead-pencils," which have to be sharpened by cutting the wood, as by means of a knife or other instrument.

B is the core of graphite or other marking

material, which, instead of being fixed in the wooden sheath with glue, as usual, is made to fit therein by friction only. The groove 55 for the core is open at the back end and may be tapered to a smaller diameter at or near the point x of the pencil, so that when the exterior of the sheath is made with a tapering point the core can be thus held with a 60 sufficient frictional and elastic grip at the point to prevent its dropping out, even should it not be held firmly elsewhere in the sheath. Other means may be provided of insuring a frictional hold on the core near the point. 65 For instance, small springs s may be let into notches in the sheath to bear against the core, as shown in Fig. 4, or a sheet-metal ferrule, as at f, Fig. 5, may be applied to the point of the cover or sheath for the same purpose. 70

To feed the core forward as it wears at the point and to hold it in place, I provide a push-rod R, Fig. 2, and a movable pawl P. The push-rod may be provided one for each gross or other suitable quantity of the pencils, but 75 each pencil has its own pawl P, put into the top of the pencil behind the core at the open back end. This pawl may be of any suitable form or material, so long as it will enter the groove in the sheath A back of the core and 80 so engage with the interior walls or bore of the sheath as to prevent the core from being pushed back, and yet permit the core to be pushed forward by means of the pusher whenever the wearing down of the point of the 85 core may require it.

In Fig. 1, at P, I have shown the pawl as made of a piece of wire doubled and with ends provided with outwardly-projecting engaging teeth. 90

At P' in Fig. 3 I have shown a modified form of the doubled or split pawl, while at P², I have shown a pawl consisting simply of a plug with saw-like or file-like teeth.

To push the core forward, the end of the 95 push-rod R is simply introduced into the open back end of the pencil-sheath, as will be understood.

I claim as my invention—

1 A pencil having a sheath open at the back 100 end for the insertion of a push-rod, a core in the sheath and a movable pawl within the bore of the sheath and in the rear of the core, as and for the purpose described.

2. A pencil having a sheath of wood or other such material open at the back end for the insertion of a push-rod, a core movable lengthwise in the sheath, and a movable pawl with 5 in the bore of the sheath and in the rear of the core, as and for the purpose described.

3. A pencil having a sheath of wood or other such material open at the back end for the insertion of a push-rod, a core movable length- 10 wise in the sheath, a movable pawl within the bore of the sheath and in the rear of the

core, and a friction means for the core near the point of the sheath, substantially as described.

In testimony whereof I have signed my 15 name to this specification in the presence of two subscribing witnesses.

BENJ. H. TOQUET.
